Attorney

UNITED STATES PATENT OFFICE

JOHN M. CHRISTMAN, OF DETROIT, MICHIGAN, ASSIGNOR, BY MESNE ASSIGNMENTS, TO PACKARD MOTOR CAR COMPANY, OF DETROIT, MICHIGAN, A CORPORATION OF MICHIGAN

PAINTING INSTRUMENT

Application filed March 26, 1928. Serial No. 264,761.

This invention relates to painting instruments and more particularly to striping instruments.

An object of the invention is to provide a striping instrument having means for guiding the instrument with precision.

Another object of the invention is to provide a striping instrument having a plurality of guide members arranged to prevent disalignment of the instrument during the manipulation thereof.

Another object of the invention is to provide a striping instrument having a plurality of rotatable guide members arranged on one side of the instrument in different planes with respect to each other, so that any liability of the instrument becoming disaligned during the use thereof is avoided.

A further object of the invention is to provide a striping instrument having a container readily adjustable to various positions, according to the plane in which the instrument is to be used.

A further object of the invention is to provide a striping instrument having a nozzle provided with a web arranged as a support and a guiding means.

A still further object of the invention is to provide a striping instrument having a flexible pivoted handle formed to fit in the hand of an operator between the thumb and forefinger and provided with suitable finger grips whereby the instrument may be readily held in engagement with the surface to be striped without liability of displacement or tiring the hand of the operator.

A still further object of the invention is to provide a striping instrument having a body portion with a plurality of rotatable guides and a gear pump adapted to be operated by one of the guides, a container connected with the intake of the gear pump, a nozzle connected with the outlet of the pump, the guides and nozzle being so positioned with respect to each other that tilting of the instrument is avoided.

Other objects of the invention will appear from the following description taken in connection with the drawings which form a part 50 of this specification, and in which:

Figure 1 is a top plan view of the instrument,

Figure 2 is a side elevation with the container and handle broken away and the face plate removed,

Figure 3 is a similar view with the handle removed and parts broken away to better illustrate the nozzle and its connection with the pump mechanism, and

Figure 4 is a sectional view taken substantially on line 4—4, Fig. 3.

Referring by numerals to the drawing, 10 represents a body portion comprising a rectangular solid having formed on each end thereof and normal thereto a lug 11 apertured as indicated at 12 to receive a pin 13. The pins 13 provide a pivotal support for a flexible handle 14. As shown, the handle is provided with apertures 15 which engage the pins 13 and the free ends of the handle 14 are curved to provide finger grips 16. This handle is sufficiently flexible to be easily connected or disconnected from the instrument and is formed to fit between the thumb and forefinger of the hand of an operator so that the instrument can be manipulated without danger of disalignment or fatigue to the hand of the operator.

The body portion 10 has arranged therein in spaced relation with respect to each other and projecting normal from one side thereof shafts 17 and 18. The shaft 17 has secured thereon a roller or guide member 19, provided with a concave face or periphery 20 adapted to fit over a moulding or bead, and the shaft 18 has journaled thereon a roller 21 having opposed flanges, one of which is beveled as indicated at 22 to engage the side of a moulding and the other has an increased diameter and is rounded as indicated at 23 to engage the surface at the base of the moulding.

The body portion 10 has a tapering bore 24 in which is positioned a plug 25, the plug being secured therein by means of a nut 26 threaded upon the smaller end thereof. The plug 25 is axially bored as indicated at 27 and has a circumferential groove 28 connected with the axial bore by a plurality of radial bores 29. The larger end of the plug 25 has

a head 30 provided with a bore 31 communicating with the axial bore 27. The bore 31 is adapted to receive the discharge end 32 of a container 33, the container being provided with a cap 34 secured on the container by means of a bayonet joint 35. By reason of this structure the container 33 may be moved from side to side or to any position which may be found desirable and advantageous in feeding fluid from the container by gravity to a pumping mechanism to be hereinafter described.

The shaft 17 projects through and beyond the body portion 10 and has keyed thereon a gear 36 flush against the body portion 10. This gear has in mesh therewith a corresponding gear 37. The gear 37 is not journaled, but notwithstanding it rotates on its own axis and is held in mesh with the gear 36 by means which will hereinafter appear. Arranged in the body of the instrument above and between the gears 36 and 37 is a passage 38 communicating with the circumferential groove 28 in the plug 25 and arranged in the body portion below and between the gears 36 and 37 is a passage 39 communicating with a transverse bore 40 which in turn communicates by a passage 41 with a nozzle 42.

Fitted over the intermeshing gears 36 and 37 is a plate 43 having arranged therein overlapping transverse bores 44 and 45. The bores 44 and 45 serve to retain the gears 36 and 37 in position and these bores cooperate with the gears 36 and 37 to provide a suitable pumping means from the passage 38 to the passage 39 and hence from the container 33 to the nozzle 42. The plate 43 is substantially the same thickness as the gears 36 and 37. If anything, the gears would be .001 or .002 of an inch thinner so that the gears might rotate within the respective bores without danger of binding and yet sufficiently tight to prevent any possibility of leakage. The plate 43 and the gears are covered and secured in place by a face plate 46 and suitable screws 47 threaded into the body portion 10, one of the screws 47 being threaded into the end of the bore 40.

The nozzle 42 is inclined to the bottom of the body 10 and has formed thereon a web 48 arranged adjacent the outlet of the nozzle and to project in the path thereof when the instrument is manipulated to paint a stripe. The web 48 is thin yet sufficiently rigid to maintain its proper relation to the nozzle; it is of sufficient proportion to span an opening or depression of small dimension and its free end is curved upwardly in order that the nozzle will ride freely over the small openings, depressions and obstructions.

In operation, the container 33 is filled with liquid paint and the instrument adjusted to the work to be performed. In adjusting the instrument to the work, the actuating roller 65 and guide 19 bears on the top of a moulding

and the roller 21 engages the moulding on one side and the base thereof on the other side. The bearing points of the rollers are in different planes with respect to each other and with respect to the nozzle, hence, any possibility of the instrument wobbling is avoided, besides, an efficient guiding means is provided.

The instrument is held firmly in position by means of the handle and the handle is provided with finger grips which materially aid the operator in keeping the rollers 19 and 21 in proper relation to the moulding. As the instrument is moved over the surface to be striped the roller 19 drives the shaft 17. This shaft carries the gear 36 which meshes with the gear 37, hence, the gears 36 and 37 are driven in opposite directions and accordingly draw the paint from the passage 38 and force it to and through the passages 39 and 40 to and through the nozzle 42. In other words, the gears 36 and 37 function as a gear pump for pumping paint from the container to and through the nozzle.

Although this invention has been described in connection with certain specific embodiments, the principles involved are susceptible of numerous other applications that will readily occur to persons skilled in the art. The invention is, therefore, to be limited only as indicated by the scope of the appended claims.

Having thus described the various features of my invention, what I claim as new and desire to secure by Letters Patent is:

1. A striping instrument comprising a body portion, a pump thereon, a container pivoted on the body portion above the pump and a nozzle on the body portion beneath the pump adapted to engage a surface to be operated upon.

2. A striping instrument comprising a body portion, a container pivoted on the body portion, a nozzle on the body portion adapted to engage a surface to be operated upon and a pump directly beneath the container and connected between the container and the nozzle.

3. A striping instrument comprising a body portion, a container pivoted on the body portion, a nozzle on the body portion adapted to engage a surface to be operated upon and a gear pump on the body portion connected between the container and the nozzle.

4. A striping instrument comprising a body portion, a container pivotally mounted on top of the body portion, a nozzle mounted on the bottom of the body portion and adapted to engage a surface to be operated upon and a gear pump on the side of the body portion connected between the container and the nozzle.

5. A striping instrument comprising a body portion having a planed side, a container pivotally mounted in the top of the body portion, a nozzle on the bottom of the body portion adapted to engage a surface to

- be operated upon, intermeshing gears positioned on the planed side of the body portion, a plate having overlapping transverse bores fitted over the gears and a face plate covering the gears. 5
6. A striping instrument comprising a body portion having a planed face, intermeshing gears positioned on the planed face, a plate having overlapping transverse bores in 10 which the intermeshing gears are positioned, a face plate over the gears and the plate having overlapping transverse bores, the body portion having inlet and outlet passages, a container connected to the inlet passage, a 15 nozzle connected to the outlet passage and means for actuating one of the gears. 7. A striping instrument comprising a body portion having a planed face, intermeshing gears positioned on the planed face, 20 a plate having overlapping transverse bores for the reception of the gears, a face plate covering the gears and the plate having overlapping transverse bores, the body portion having inlet and outlet passages, a container 25 pivotally connected to the inlet passage, and a nozzle connected to the outlet passage and adapted to engage a surface to be operated upon, means for driving one of the gears and means for guiding the instrument. 30 8. A striping instrument comprising a body portion having a planed face, a plurality of guides rotatably mounted on the body portion, a handle pivoted intermediate the guides and the body portion, intermeshing gears positioned on the planed face, a plate having overlapping transverse bores in 35 which the gears are positioned, a face plate covering the gears and the plate having overlapping transverse bores, the body portion 40 having inlet and discharge passages, a container pivotally connected to the inlet passage and a nozzle connected to the outlet passage. 9. A striping instrument comprising a body portion, guides therefor, a handle pivoted to the body portion, a gear pump on the body portion, a nozzle on the body portion adapted to engage a surface to be operated upon, the body portion having a tapering bore, a tapering plug fitted therein, means for retaining the plug in position, the 50 plug having an axial bore and a circumferential groove connected therewith, a container carried by the plug in an inclined position and communicating with the axial bore, the body portion having a passage leading from the circumferential groove in the plug to the intake of the pump and a passage leading from the outlet of the pump to the nozzle. 55 10. A striping instrument comprising a body portion, a nozzle on the body portion, a plurality of guides arranged on one side of the body portion and a handle pivoted on the body portion in a plane intermediate the guides and the nozzle. 60 11. A striping instrument comprising a body portion having a nozzle arranged in the bottom thereof, a plurality of rotatable guides on one side of the body portion, the nozzle and the guides being arranged in different vertical planes whereby tilting of the instrument is prevented. 70 12. A striping instrument comprising a body portion, a container mounted in the top thereof, a nozzle mounted in the bottom of the body portion and adapted to engage a surface to be operated upon, a gear pump connected between the container and the nozzle, a plurality of guides rotatably mounted on one side of the body portion, the nozzle 75 and guides being positioned in different vertical planes to prevent tilting of the instrument and means connecting one of the guides to the pump for the operation thereof. 13. A striping instrument comprising a body portion, a nozzle on the body portion, a pump in the body and a freely movable liquid container mounted on the body. 80 14. A painting instrument comprising a body adapted to engage the work in a pre-determined position and a paint container pivotally mounted on the body for movement transversely of the line in which the instrument is adapted to move. 90 15. A painting instrument comprising a body adapted to engage the work in a pre-determined position and a paint container pivotally mounted on the body for movement transversely of the line in which the instrument is adapted to move and at an angle with 95 reference to a perpendicular to the surface of the work. 16. In a striping instrument, the combination with a body and a nozzle on said body, of a freely movable container pivotally mounted on the body normal to the surface to be striped, the body and container having passageways therein whereby the container is always connected in communication with the nozzle. 105 17. In a striping instrument the combination with a body and a nozzle on the body, of a container pivotally mounted on the body, and a pumping element positioned intermediate the container and the nozzle. 115 18. In a painting instrument a body, a roller fixed to the body and arranged in a plane on one side thereof, a container associated with the body, a pump carried within the body communicating with the container, and a nozzle depending from the body spaced laterally from the roller and communicating with the pump, the discharge end of said nozzle being formed with an elongated bearing surface extending from the outlet opening and arranged in a plane to bear against the surface traversed by the instrument, the roller and bearing surface of the nozzle supporting the instrument upon the surface 120 125 130

traversed in a relation to prevent side tilting thereof.

19. In a striping instrument, a body having a container associated therewith, a pump within the body communicating with the container, a nozzle depending from the body and adapted to bear against the surface traversed at its discharge end, said nozzle communicating with the pump, a pair of guide roller means supported at one side of the body and arranged to align in the direction of the instrument travel, one of said rollers being formed to ride upon a beaded surface and the other roller being formed to engage the side rise of such beaded portion of a surface traversed, and driving means between one of the rollers and the pump.

In testimony whereof I affix my signature.
JOHN M. CHRISTMAN.
